6 Claims. (Cl. 89—21)

(Granted under Title 35, U.S. Code (1952), sec. 266)

The invention described herein may be manufactured and used by or for the Government for governmental purposes without the payment of any royalty thereon.

This invention relates to artillery guns for firing shells having cases which must be ejected before reloading can be accomplished and pertains more particularly to ejector systems for such guns.

It is the object of this invention to provide for artillery guns of split-chamber type, which are adapted for firing a round having a metallic case, an ejector for automatically dispelling the fired case, which ejector is mounted to the outside of the gun so as not to change the basic internal design thereof and which utilizes the retraction and pivotal motion of the breech assembly for its operation.

It is also the object of this invention to provide such an ejector which is simple but rugged in design and positive in operation.

The specific nature of the invention as well as other objects and advantages thereof will clearly appear from a description of a preferred embodiment as shown in the accompanying drawings in which:

FIG. 1 is a side view of the breech end of a split-chamber gun showing the breech assembly in locked battery position with the view partially cross-sectioned to show a part of the internal structure of the gun;

FIG. 2 is an end view of the gun showing the breech assembly in the locked battery position;

FIG. 3 is a fragmentary view similar to FIG. 1 but showing the breech assembly in its retracted position prior to roll-over to the open position and the cam follower seared in the locking section of the cam slot;

FIG. 4 is a view taken along line 4—4 of FIG. 3;

FIG. 5 is a fragmentary side view similar to FIGS. 1 and 3 but showing the relationship of the arm relative to the case and the stud relative to the external surface of the coupling section during roll-over of the breech assembly to the open position;

FIG. 6 is a fragmentary end view showing the parts as related in FIG. 5;

FIG. 7 is a view similar to FIG. 5 but showing the breech assembly in the open position and the fired case partially ejected;

FIG. 8 is a fragmentary end view showing the parts as related in FIG. 7;

FIG. 9 is a view similar to FIGS. 5 and 7 but showing the arm actuated clear of the fired case when the cam follower is at the rear end of the tail of the translational displacement of the breech section of the cam slot;

FIG. 10 is a fragmentary end view showing the parts as related in FIG. 9;

FIG. 11 is a perspective view of the rear end of the gun showing the breech assembly in the retracted open position and the fired case ejected from the tube; and

FIG. 12 is an exploded perspective view of the extractor.

Shown in the figures is an artillery gun 12 which is of split-chamber type and is adapted for firing a cartridge 14 having a projectile (not shown) and a case 16 with an extractor groove 18 around the base thereof. Gun 12 includes a tube 20 having a bore with a concentric front chamber-section 24 formed at the rear end thereof. A cylindrical coupling 26 is attached and locked to the rear of tube 20, thereby forming an integral unit.

5 A breech assembly 28 is mounted on coupling 26 and tube 20, as hereinafter described, for longitudinal displacement between a rearward retracted and a forward battery position and for pivotal roll-over between an open and an in-line position (relative to the tube) around an axis disposed parallel to the axis of the tube. Breech assembly 28 includes a carrier 30 and a chamber member 32 mounted for rotation therewith between a locked and an unlocked position. Carrier 30 is mounted on coupling 26 by means of a cylinder 34, which is attached to the carrier, and a cooperating hydraulic cylinder housing 38 which is attached to the coupling by a bracket 40. Piston 34 and cylinder housing 38 are positioned underneath coupling 26 and to the right of the central vertical plane thereof.

10 15 A front portion 42 of chamber member 32 is receivable by coupling section 26 when breech assembly 28 is in the battery position and a rear chamber section 44 extends rearwardly into the chamber member to receive the rear portion of case 16 and complete the chambering thereof when the breech assembly is in the battery position. Interrupted sector threads 45 on the outside of front portion 42 and on the inside of coupling section 26 lock breech assembly 28 in the battery position when chamber member 32 is rotated in a clockwise direction to the locked

20 25 position. A conventional operating mechanism (not shown) which is housed within cylinder 34 and cylinder housing 38 and is not a part of this invention provides for the sequential rotation of chamber member 32 to the unlocked position followed by translational displacement

30 35 of breech assembly 28 to the retracted position and then the roll-over thereof in a counterclockwise direction to the open position, and the reversal of these steps, responsive to the application of hydraulic pressure into cylinder housing 38. Round 14 is loaded into tube 20 manually

40 45 and, when fully positioned therein, the base of case 16 is approximately even with the rear end of coupling section 26. Fired case 16 is ejected automatically after roll-over of breech assembly 28 to the open position by an ejector 46 mounted on carrier 30 and a cooperating latch 48

50 mounted on cylinder housing 38. Ejector 46 includes a housing 50 which is attached to carrier 30 and is arranged to extend forwardly therefrom so that the front end is located slightly rearward of the rear end of coupling section 26 when breech assembly 28 is in the retracted

45 position.

Extending through housing 50 is a cylindrical hole 52 the axis of which is disposed parallel to the axis of tube 20. The rear end of hole 52 is closed by a threaded

55 59 plug 54. Supported within hole 52 is a rod 56 which is terminated at the rear end by a head 58 the outside diameter of which is similar to the inside diameter of the hole so as to be slidable therein. Mounted on the front end of housing 50 is a tubular cam member 60 which

55 60 slidably receives the front portion of rod 56. Cam member 60 is provided with an annular flange 62 spaced from the rear end so as to form a stub portion 63 which is received by hole 52 and the flange has contact with the front end of housing 50 to correctly position the cam member longitudinally.

60 65 A screw 64 through housing 50 and stub portion 63 secures cam member 60 to the housing. A torsion-compression spring 66 is wound around rod 56 between head 58 and the end of stub portion 63 and is preloaded therebetween so as to bias the rod rearwardly relative to housing 50. The rear end of spring 66 is anchored to head 58 by means of a channel 67 therein and the front end of the spring is anchored to housing 50 by means of a channel 69 in cam member 60. Spring 66 is coiled so as to be wound when rod 56 is rotated in a clockwise direction.

70 75 Provided in cam member 60 forwardly of flange 62 is a cam slot 68 which slidably receives a cam follower

79 threadingly secured to rod 56, whereby longitudinal displacement of the rod is converted to rotational displacement thereof according to the configuration of the cam slot as defined hereinafter. Fixed to the front end of rod 56 is an arm 72 which extends thereacross. One end of arm 72 is machined to form a blade 74 which is engageable with extractor groove 18 of fired case 16 when the arm is swung to an engaged position. Fixed to the opposite end of arm 72, which will be referred to hereinafter as contact end 76, is a stud 77 which extends forwardly therefrom for camming contact with the outside surface of coupling section 26 to function as herein-after described.

Cam slot 68 is formed to include a straight, longitudinally disposed dwell section 78 along which cam follower 70 moves during translational travel of breech assembly 28. Dwell section 78 leads forwardly into a locking section 80 which, as shown in FIG. 12, extends in a counterclockwise direction from the dwell section and which forms a wall 82 disposed at right angles to the adjacent side of the dwell section noted at 84. Dwell section 78 leads rearwardly into a tail section 86 which extends angularly in a rearward and clockwise direction therefrom.

Latch 48 includes a mounting case 88 in which a plunger 90 is disposed for sliding vertical displacement between an extended latching position and a depressed unlatching position. A spring 92 biases plunger 90 to the latching position. Formed in the top portion of plunger 90, which extends above case 88, is a cam surface 94 which extends upwardly and forwardly to the top end of the plunger. Shaft 96 has a camming engagement with plunger 90 to provide manual depression of the plunger when a handle 98 fixed to the shaft is manually rotated.

Thus, when hydraulic pressure is applied to cylinder housing 38, after gun 12 is fired, chamber member 32 is rotated to the unlocked position, disengaging the threads 45, and breech assembly 28 starts its translational displacement from the battery to the retracted position. As breech assembly 28 moves rearwardly, contact end 76 contacts plunger 90, whereby arm 72 is stopped while breech assembly 28 with housing 50 thereon continues rearwardly compressing spring 66. During the initial portion of the relative movement between housing 50 and rod 56, cam follower 70 moves along tail portion 86 rotating arm 72 so as to move blade 74 into close proximity to extractor groove 18, after the breech assembly is retracted sufficiently to provide a clearance for the blade. During continued retraction of breech assembly 28, cam follower 70 moves along dwell section 78 with the torque of spring 66 holding the cam follower pressed against side 84 of the dwell section while the spring at the same time is being compressed between head 58 and cam member 60.

When breech assembly 28 reaches its retracted position, cam follower 70 is positioned forwardly of side 84, whereby the torque of spring 66 snaps the cam follower into locking section 80. This rotary displacement of arm 72 causes contact end 76 to be moved out of contact with plunger 90 but rod 54 is held extended and spring 66 compressed, during the roll-over of breech assembly 28, by the searing contact of cam follower 70 with wall 82. During the final portion of the roll-over, stud 77 contacts the outside surface of coupling section 26. Stud 77 is so related to the outside of coupling 26 in its location and path of movement, as shown in FIGS. 5 and 6, that the contact therebetween cams contact end 76 downwardly and, thereby, blade 74 upwardly into full engagement with the extractor groove 18 of fired case 16. At the same time, cam follower 70 is moved out of contact with wall 82 and into dwell section 78 so that arm 72 is released and the energy in compressed spring 66 is applied to fired case 16 for ejection thereof from tube 20.

Cam follower 70 moves rearwardly with arm 72, during ejection of fired case 16 and, during the final rear-

ward displacement of the arm, the cam follower moves into tail section 86, whereby the arm is rotated to displace blade 74 from extractor groove 18 and clear of the case during continued ejection thereof from gun 12.

In the closing cycle of the gun operation, hydraulic pressure is applied to cylinder housing 38, after cartridge 14 is loaded to tube 20, and thereby breech assembly 28 proceeds through the roll-over sequence to the in-line position followed by forward travel to battery position and rotation of chamber member 32 to the locked position. As breech assembly 28 moves forwardly, contact end 76 contacts cam surface 94 on plunger 90 to cause downward displacement thereof for free forward displacement of arm 72 thereby.

If an operator should wish to open the breech of tube 20 without ejecting cartridge 14 therefrom, handle 98 is rotated to depress plunger 90 so that arm 72 will not be stopped thereby, to initiate the operating functions of ejector 46 when breech assembly 28 is displaced rearwardly to the retracted position.

Although a particular embodiment of the invention has been described in detail herein, it is evident that many variations may be devised within the spirit and scope thereof and the following claims are intended to include such variations.

We claim:

1. An ejector and a cooperating latch for an artillery gun having a tube and a breech assembly mounted on the tube for translational displacement from a battery to a retracted position followed by pivotal movement from an in-line to an open position relative to the tube around an axis disposed parallel to the axis thereof to provide clearance for ejection of a fired case from the tube and the loading of a cartridge thereinto, the case being provided with an annular extractor groove adjacent the base thereof and the gun being provided with a chamber section in the tube arranged to locate the base of the case approximately even with the rear end of the tube when loaded thereinto, the latch including a mounting case fixed on said tube, a plunger mounted in said mounting case for vertical displacement between a depressed and an extended position and a spring arranged for biasing said plunger to the extended position, the ejector comprising a housing secured to the breech assembly for displacement therewith, a rod slidably mounted in said housing for longitudinal and rotary movement relative thereto and arranged to extend forwardly therefrom, an arm mounted across the front end of said rod, a blade formed on one end of said arm and arranged to be engageable with the extractor groove of the case in the tube, when rotated thereto, a contact end formed on the opposite end of said arm so as to be contactable with said plunger during displacement of said breechblock to the retracted position for holding said rod against translational displacement with said breechblock and so as to be out of contact with said plunger when said blade is in engagement with said extractor groove, a torsion-compression spring operationally disposed between said housing and said rod so as to be compressed during relative translational movement therebetween and so as to bias said arm rotationally in a direction to engage said blade with the extractor groove, means for displacing said arm to engage said blade with the extractor groove and release said contact end from said plunger when the breechblock reaches the retracted position during displacement from the battery position, sear means for releasably securing said rod in the extended position after said contact end is released from said plunger, and cam means for disengaging said rod from said sear means at the completion of the pivotal movement of said breechblock from the in-line to the closed position to release said arm for ejecting the fired case from the tube.
2. The ejector as defined in claim 1 wherein said ejector includes a tubular cam member mounted on the front end of said housing to slidably receive said rod there-

through, a cam slot formed in said cam member, a cam follower fixed to said rod and arranged to be slidily received by said cam slot, said cam slot being provided with a longitudinal dwell section having a side slidily contacted by said cam follower by torsional bias of said spring during displacement of the breechblock from the battery to the retracted position, wherein said means for displacing said arm to engage said blade with the extractor groove includes the torsional bias of said spring and a lock section formed at one end of said dwell section so as to permit displacement of said cam follower by said spring when the breechblock is in the retracted position, and wherein said sear means includes a wall formed in said locked section so as to contactingly block translational displacement of said arm by said spring.

3. The ejector as defined in claim 2 and including a stud fixed on said contact end so as to cammingly contact the outside surface of the tube during rotation of

the breechblock to the open position for rotating said arm to displace said cam follower out of contact with said wall into said dwell section.

4. The ejector as defined in claim 2 and including means for displacing said blade clear of the extractor groove during ejection of the case from the tube.

5. The ejector as defined in claim 2 and including a tail section angularly generated in said cam slot for displacing said blade free of the extractor groove when said cam follower travels along said cam slot during ejection of the case.

6. The latch as defined in claim 2 and including means for manually actuating said plunger to the depressed position to render the ejector inoperative.
